EVAPORATOR DISTRIBUTOR HEAD

Ernst Witzel, Racine, Wis., assignor to Young
Radiator Company, Racine, Wis., a corporation
of Wisconsin

Application July 14, 1937, Serial No. 153,626

6 Claims. (Cl. 62—126)

Modern evaporators are made in from two to 12 or more separate sections. It is desirable to distribute the refrigerant equally into each section. This is difficult to accomplish because of 5 the nature of refrigerants. They are not always completely in liquid state when they reach the distributor, the pressure varies considerably and is frequently controlled by valves operating on the on-and-off principle and when otherwise 10 controlled the pressure and supply is erratic and uncertain as to the amount of gas mixed with the liquid refrigerants.

The object of the present invention is to provide a very simple, light and easily manufactured distributor head which may be easily connected to the various coils and to the supply, and a head which will distribute the refrigerant and the gasses mixed therewith equally to the several coils.

20 To these and other useful ends my invention consists of parts, combinations of parts, or their equivalents as hereinafter described and claimed, and shown in the accompanying drawing in which:

25 Fig. 1 is a transverse sectional view of my improved distributor head taken on line 1—1 of Figure 2.

Fig. 2 is a vertical elevation of my improved distributor head taken on line 2—2 of Figure 1.

30 Fig. 3 is a top view having the cap removed and illustrating my improved distributor head having eight outlets instead of four.

Fig. 4 illustrates a vertically sectioned view of a modification.

35 In Figure 2 I have shown a fraction of a four section evaporator which is, in its entirety, designated by reference character A. This evaporator has four separate coils, the top coil being shown fractionally.

40 The evaporator coils as illustrated each consists of tube 10 having fins 11 and the expanded end 12 by means of which the various coils are connected through suitable loops.

I prefer to mount the various coils at each end 45 in header plates 13 as illustrated, and secure the expanded ends of each of the coils to this plate. The inlet ends of the coils however are supplied with a sleeve 14 with which to make connections with the various refrigerant supply tubes. Each 50 individual section of an evaporator has an inlet as shown.

55 My improved distributor head consists of a bottom member 15 through the center of which the inlet tube 16 extends terminating preferably

as at 17, this tube at its inlet end being supplied with a suitable elbow 18.

I provide outlet openings 20, 21, 22 and 23 which are evenly spaced around the inlet tube as illustrated in the various figures. The individual evaporator coils are connected to these head outlets by means of tubes 24, 25, 26 and 27. I supply preferably a round in cross section cylinder 30 having a cap 31 thus forming a chamber which must clearly be positioned slightly above 10 the highest evaporator coil as illustrated in Figure 2.

In Figures 1 and 2 I illustrate a distributor head having 4 outlets and in Figure 3 I illustrate a distributor head having 8 outlets. Thus it will 15 be seen from these figures that any reasonable number of outlets may be provided.

I provide partition walls 32 as clearly illustrated in Figures 1 and 2. These walls are exactly alike and fabricated so as to fill the space in the 20 chamber contacting each other as at 33 which point is concentric with inlet tube 16. These partitions radiate outwardly from point 33 and answer to separate the outlets or to form separate connections from inlet tube 16 to the individual outlets. I preferably extend these partition walls into the tube 16 as illustrated in Figure 2, these extensions terminating as at 34. Thus the beginning of the inlet to the various outlets is at 34 and each occupying an equal 30 area of tube 16; thus as the refrigerant rises in tube 16 these partitions at 34 will separate the refrigerant into equal volumes and it will then pass directly into the outlets.

In Figure 2 I have illustrated the top evaporator coil as being connected to outlet 20 by means of tube 24. The top evaporator coil may be very little below the bottom of the distributor head and the bottom coil may be a considerable distance below the distributor head in the type 40 of evaporator shown. Therefore the longer tubes might possibly act as syphons; thus to unbalance the quantity of refrigerant fed into the coils.

In the present invention I prevent this syphoning effect by removing a small portion of the 45 partitions, preferably at their corners as at 35. Thus the pressure or vacuum in each of the spaces formed by partitions 32 will always remain the same.

In installations where the elbow 18 is close to 50 the head, centrifugal action may cause the refrigerant as it enters tube 16, to hug the far side of the wall of the tube. In order to insure against thus unbalancing the refrigerant I provide a spiral 36 which will cause the refrigerant to be 55

agitated and whirled around the periphery of the tube and evenly distribute the refrigerant between the partitions at 34.

In Figure 4 I illustrate a modification wherein 5 the side wall and bottom of the chamber are cast integral having a cap 40 thus forming an enclosure similar to that shown in Figure 2; differing only in the position of the outlets 41, of which there may be any suitable number. In this design however these outlets are slightly differently positioned and they diverge outwardly somewhat thus to provide more room between the tubes for bonded or for screw threaded couplings.

Having thus shown and described my invention 10 15 I claim:

1. An evaporator distributor head comprising a vertically positioned chamber having a horizontally positioned bottom, a refrigerant inlet tube centrally positioned in said bottom, refrigerant outlet tubes in said bottom being evenly spaced around said inlet, vertically positioned partition walls radiating from the center of said inlet and dividing the space in said chamber into individual passageways between said inlet and 20 outlets, said partitions having portions removed at their upper edges to thereby form vents between said individual passageways.

2. An evaporator distributor head comprising a vertically positioned chamber having a horizontally positioned bottom, a refrigerant inlet tube positioned centrally in said bottom, refrigerant outlet tubes in said bottom being evenly spaced around said inlet, partition walls radiating from the center of said inlet and dividing the 30 space in said chamber into individual passageways between said inlet and outlets, said inlet having means adapted to cause the refrigerant to travel spirally therein.

3. A distributing head of the class described, 35 comprising an inverted cap having a bottom to thereby form a chamber, a refrigerant inlet tube

positioned centrally in said bottom, refrigerant outlet tubes in said bottom being evenly spaced around said inlet, partition walls radiating from the center of said inlet and dividing the space in said cap into individual channels between said inlet and outlets, said partitions extending a distance into said inlet. 5

4. A distributor head of the class described, comprising a vertically positioned chamber having a horizontally positioned bottom, a refrigerant inlet tube centrally positioned in and extending vertically a distance above said bottom, a number of outlet openings in said bottom being equally spaced around said inlet tube, partition walls radiating from the center of said inlet tube dividing the space in said chamber into independent channels from said inlet to said outlet tubes. 10 15

5. A distributor head of the class described, comprising a chamber having a horizontally positioned bottom, a centrally positioned refrigerant inlet tube in said bottom and extending vertically a distance into said chamber, a number of tube outlets in said bottom being equally spaced around said inlet tube, partition walls radiating from the center of said inlet tube and dividing the space 20 25 in said chamber into independent channels between said inlet and outlets, said partitions extending a distance into the end of said inlet tube.

6. A distributor head of the class described, comprising a chamber having a horizontally positioned bottom, a refrigerant inlet tube centrally positioned in said bottom and extending a distance into said chamber, a number of outlet tubes in said bottom being equally spaced around said inlet tube, partition walls radiating from the center of said inlet tube dividing the space in 30 35 said chamber into independent channels between the end of said inlet tube and outlets, said partitions having portions removed at their tops to thus form passageways between said channels.

40 ERNST WITZEL.
